(57) **ABSTRACT**
A new and distinct cherry tree variety, *Prunus avium* L., cv. 'Sucherryone' is characterized by very early ripening, large-size fruit, reniform fruit shape and high acidity.

1 Drawing Sheet

1

Latin name of the genus and species claimed: *Prunus avium* L.

Variety denomination: 'Sucherryone'

BACKGROUND AND SUMMARY OF THE INVENTION

This invention relates to the discovery and asexual propagation of a new and distinct variety of cherry, *Prunus avium* L. 'Sucherryone'. The new variety was first selected in May 2007 by Terry Bacon as breeder number 'CH827'. The new variety was first evaluated by Terry Bacon near Wasco, Calif. in Kern County. The variety 'Sucherryone' was originated by hybridization.

The new variety 'Sucherryone' is characterized by very early ripening, large-size fruit, reniform fruit shape and high acidity.

The seed parent is 'Brooks' (unpatented), and it was open pollinated. The parent varieties were first crossed in February 2003, with the date of first sowing being February 2004 and the date of first flowering being February 2007. The new cherry variety 'Sucherryone' was first asexually propagated by Terry Bacon near Wasco, Kern County, Calif. in January 2013 by dormant grafting.

The new variety 'Sucherryone' is similar to its seed parent, 'Brooks' in that they both have similar shaped fruit, but the bloom of the new variety 'Sucherryone' starts 9 days earlier than for 'Brooks' and harvest starts about 9 days earlier than for 'Brooks'. The new variety 'Sucherryone' also differs from 'Brooks' in that the chilling requirement is 750 chill units compared to 850 chill units for 'Brooks'.

The harvest of the fruit of the new variety 'Sucherryone' starts about 8 days earlier than 'Tulare' (unpatented) and the fruit shape of the new variety is reniform compared to cordate for 'Tulare'. The new variety 'Sucherryone' also differs from 'Tulare' in that the chilling requirement is 750 chill units compared to 800 chill units for 'Tulare'.

The new variety 'Sucherryone' has a similar fruit shape as 'Bing' (unpatented), but the harvest of the new variety 'Sucherryone' starts about 14 days earlier than that of

2

'Bing'. The frequency of double pistils in the new variety 'Sucherryone' is rare compared to frequent for 'Bing'. The harvest of the new variety 'Sucherryone' starts at about the same time as that of 'Minnie Royal' (PP12,942), but the fruit shape of the new variety is reniform compared to cordate for 'Minnie Royal'. The new variety 'Sucherryone' also differs from 'Minnie Royal' in that the chilling requirement for 'Sucherryone' is 750 chill units compared to 650 chill units for 'Minnie Royal'.

The new variety 'Sucherryone' has been shown to maintain its distinguishing characteristics through successive asexual propagations by, for example, cuttings and grafting onto 'Wieroot 158' (unpatented) rootstock.

BRIEF DESCRIPTION OF THE DRAWING

15 The accompanying color photographic illustration shows typical specimens of the foliage and fruit of the present new grape variety 'Sucherryone'. The illustration shows the upper and lower surfaces of the leaves and exterior and sectional views of the fruit. The photographic illustration was taken shortly after the fruit was picked and the colors are as nearly true as is reasonably possible in a color representation of this type.

DETAILED DESCRIPTION OF THE PREFERRED EMBODIMENT

20 Throughout this specification color names beginning with a small letter signify that the name of that color as used in common speech is aptly descriptive. Color names beginning with a capital letter designate values based upon The R.H.S. 25 Colour Chart published by The Royal Horticultural Society, London, England, 1986.

30 The descriptive matter which follows pertains to 8 year old 'Sucherryone' trees grown in the vicinity of Wasco, Kern County, Calif. during 2017, and is believed to apply to plants 35 of the variety grown under similar conditions of soil and climate elsewhere.

TREE

General: (Measurements taken on 8 year old trees unless otherwise noted.)

<i>Size</i> .—Medium. Reaches a height of approximately 3 meters with normal pruning.	5	<i>Color of upper side and intensity</i> .—Medium intensity; about Dark Green 136B.
<i>Vigor</i> .—Strong. Top shoot growth of about 1.5 meters during the first growing season.		<i>Color of lower side</i> .—About Light Green 138C.
<i>Growth</i> .—Semi-upright.	5	<i>Angle at base</i> .—Rounded.
<i>Productivity</i> .—Productive. Produces ample fruit set annually.		<i>Angle at apex</i> .—Acuminate.
<i>Fertility</i> .—Self-incompatible; pollinator required.		<i>Vein color</i> .—About Light Green 139D.
<i>Hardiness</i> .—Hardy in all fruit growing areas of California. Winter chilling requirement is approximately 750 hours at or below 7.2° C.	10	<i>Presence of red coloration of mid-vein on the lower side</i> .—Absent.
<i>Disease resistance/susceptibility</i> .—No specific testing for relative plant disease resistance/susceptibility has been undertaken. Under close observation in Kern County, Calif., no particular plant/fruit disease resistance/susceptibility has been observed.	15	<i>Surface texture</i> .—Smooth on both top and bottom surfaces.
Trunk: (Measurements at approximately 30 cm above the soil line.)		<i>Shape in the cross section</i> .—Slightly up-folded.
<i>Diameter</i> .—Approximately 25 cm.	20	<i>Leaf blade tip</i> .—In the plane of the leaf.
<i>Texture</i> .—Medium shaggy; increases with age of tree.		<i>Undulation of margin</i> .—Slight.
<i>Trunk color</i> .—About Light Black 202C with highlights of Dark Greyed-Orange 176B, becoming darker with age.		<i>Margin</i> .—Shallow serrate.
Branches: (Measurements at approximately 90 cm above the soil line.)	25	<i>Ratio length of leaf blade:length of petiole</i> .—Medium: 3.7:1.
<i>Diameter</i> .—Approximately 13 cm.		<i>Venation</i> .—Pinnately veined.
<i>Texture</i> .—Medium shaggy; increasing with tree age.		<i>Petiole</i> :
<i>Color</i> .—About Light Black 202C with highlights of Medium Greyed-Orange 176C, becoming darker with age.	30	<i>Average length</i> .—Medium; approximately 30 mm.
<i>Lenticels density</i> .—Approximately 0.2 per cm ² .		<i>Average diameter</i> .—Approximately 2 mm.
<i>Lenticels color</i> .—About Medium Greyed-Green 198B.		<i>Color</i> .—About Medium Green 139C.
<i>Lenticels length</i> .—Approximately 10 mm.		<i>Stipules</i> :
<i>Lenticels width</i> .—Approximately 3 mm.	35	<i>Number/leaf bud</i> .—Usually 2.
Shoots: (Data taken in May at the midpoint of current-season growth.)		<i>Typical length</i> .—Approximately 11 mm.
Young shoots:		<i>Color</i> .—About Dark Greyed-Orange 166A when dried.
<i>Anthocyanin coloration of apex (during raping growth)</i> .—Weak.	40	<i>Persistence</i> .—Falls off.
<i>Pubescence of apex during rapid growth</i> .—Medium.		<i>Glands (Nectaries)</i> :
Current season shoots:		<i>Form</i> .—Reniform.
<i>Thickness at midlength</i> .—Medium; approximately 7 mm.		<i>Average number and arrangement</i> .—Usually 2, alternating. Predominately on petiole.
<i>Length of internodes</i> .—Normal; mostly 2 cm.	45	<i>Dimension</i> .—Approximately 2 mm long by 1.4 mm wide.
<i>Color topside</i> .—About Light Green 138C.		<i>Color</i> .—About Dark Greyed-Red 178B in September.
<i>Color underside</i> .—About Light Green 138C.		<i>Vegetative buds</i> : (Data taken in September at midpoint of current-season growth)
<i>Lenticels density</i> .—Few; about 1 per cm ² .		<i>Bud dimensions</i> .—Approximately 10 mm long by 4 mm wide.
<i>Lenticels color</i> .—About Medium Greyed-Green 198B.		<i>Bud shape</i> .—Conical.
<i>Lenticel dimensions</i> .—Width: Approximately 1 mm. 50		<i>Color</i> .—About Dark Greyed-Orange 177A.
Length: Approximately 2 mm.		FLOWERS
<i>Presence of anthocyanin coloration</i> .—Absent or very sparse.		
One year old shoots:		45 <i>General</i> :
<i>Number of flower buds per spur</i> .—About 10, varies from 3 to 12.	55	<i>Type of bloom</i> .—Showy.
		<i>Diameter of fully opened flower</i> .—Approximately 28 mm.
		<i>Flower aroma</i> .—Medium-strong.
		<i>Time of beginning of flowering</i> .—Approximately March 7.
		<i>Flower blooming period</i> .—First Bloom: Approximately March 7. Full Bloom: Approximately March 11.
		<i>Location of first bloom</i> .—Tips of one-year-old shoots.
		<i>Location of full bloom</i> .—Central part of the tree canopy.
		<i>Duration of bloom</i> .—Approximately 10 days.
Leaves: (Data taken in September at the midpoint of current-season growth)	60	Flower buds: (Data taken in September at midpoint of current-season growth)
<i>Average length</i> .—Medium; approximately 11 cm without petiole.		<i>Bud dimensions</i> .—Approximately 8 mm long by 3 mm wide.
<i>Average width</i> .—Medium; approximately 4.5 cm.		<i>Bud shape</i> .—Conical.
<i>Length:width ratio</i> .—Medium; about 2.4:1.	65	<i>Color</i> .—About Dark Greyed-Orange 177B.
<i>Shape</i> .—Elliptic.		<i>Number of flowers per flower bud</i> .—Average 4; varies from 2 to 5.

FOLIAGE

Leaves: (Data taken in September at the midpoint of current-season growth)	60
<i>Average length</i> .—Medium; approximately 11 cm without petiole.	
<i>Average width</i> .—Medium; approximately 4.5 cm.	
<i>Length:width ratio</i> .—Medium; about 2.4:1.	
<i>Shape</i> .—Elliptic.	65

<i>Number of buds per spur.</i> —Average 7; varies from 5 to 9.		<i>Width of stem cavity.</i> —Medium, about 4 mm.
Pedicels:		<i>Prominence of suture.</i> —Absent or very weakly conspicuous.
Length.—Approximately 12 mm.		Fruit skin:
Color.—About Medium Green 138B.	5	Thickness.—Intermediate, typical of most varieties.
Sepals:		Adherence to flesh.—Strong.
Number.—5.		Taste.—Neutral.
Shape.—Triangular.		Surface texture.—Smooth.
Position.—Adpressed to petals, alternate with petals.	10	Bloom.—Wanting.
Length.—Approximately 7 mm.		Tendency to crack.—None during dry weather. Slight tendency to crack in wet weather but varies with stage of maturity.
Width.—Approximately 5 mm.		<i>Number of lenticels on skin.</i> —Medium, approximately 12 per cm^2 .
Surface texture.—Glabrous on outer and inner surfaces.		Color.—About Medium Red 46B, becoming Dark Purple 79A.
Color.—About Dark Greyed-Purple 184A.	15	Flesh:
Petals:		Ripens.—Evenly.
Number.—5.		Color.—At full maturity about Dark Red 53B to Dark Red 53A.
Arrangement.—Usually free.		Color of juice.—About Light Red 53D at full maturity.
Color.—About White 155A.		Flavor.—Mildly tart-sweet.
Surface texture.—Smooth on upper and lower surface.	20	Firmness.—Firm; comparable to most commercial varieties.
Dimensions.—Approximately 16 mm long by 14 mm wide.		Juiciness.—Medium; able to squeeze free juice easily.
Shape.—Circular.		Sweetness.—Medium; about 17% brix at harvest.
Apex shape.—Rounded.		Acidity.—High for cherries; about 0.82% titratable acidity.
Base shape.—Narrows at point of attachment.		Texture.—Firm.
Undulation of margins.—Slightly undulating.	25	Fibers.—Few, small and tender.
Frequency of flowers with double petals.—Rare.		Stone:
Stigma:		Stone size.—Medium. Length: Approximately 9 mm. Diameter Facing Suture: Approximately 6 mm. Diameter Perpendicular to Suture Plane: Approximately 9 mm.
Position compared to anthers.—Slightly higher.		Ratio weight of fruit: weight of stone.—Medium, about 53:1.
Stamens:		Color.—About Medium Greyed-Yellow 161C when dried.
Number.—About 38; varies from 34 to 40.	30	Shape in lateral view perpendicular to suture.—Circular.
Filament length.—Average 12 mm.		Shape in ventral view facing suture.—Broad elliptic.
Filament color.—About White 155A.		Shape in basal view.—Broad elliptic.
Pollen.—Present.		Base shape.—Flat.
Flower pollen color.—About Light Yellow 3D.	35	Apex shape.—Rounded.
Pistil:		Ridges.—A small narrow ridge on each side of suture, extending from base to apex.
Length.—Approximately 16 mm.		Symmetry in lateral view.—Symmetric or slightly asymmetric.
Surface.—Glabrous.		Surface.—Nearly smooth except for small ridges near the suture.
Frequency of supplementary pistils.—Rare.	40	Width of stalk end.—Narrow, approximately 1 mm.
FRUIT		
General: (Description taken at firm-mature near Wasco, Kern County, Calif).		Tendency to split.—None.
Date of first pick.—Approximately April 28.	45	Adherence to flesh.—Semi-freestone.
Date of last pick.—Approximately May 8.		Market:
Time of beginning of fruit ripening.—Very early.		Use.—Dessert.
Stem:		Market.—Local and long distance.
Length.—Medium, approximately 24 mm.		Storage quality.—Good, held well for 3 weeks in cold storage at 33° F. and maintained good appearance and eating quality.
Thickness.—Medium, approximately 2 mm.		Shipping quality.—Good, showed minimal bruising or scarring during harvest, packing and shipping trials.
Color.—About Light Green 139D.	50	
Abscission layer between stalk and fruit.—Absent.		
Fruit size:		
Size.—Large.		
Weight.—About 8 g.	55	
Height.—About 22 mm.		
Diameter perpendicular to suture.—Approximately 24 mm.		
Diameter ventral side, facing suture.—Approximately 26 mm.	60	
Fruit shape:		
Shape viewed from apex.—Circular.		
Shape ventral side, facing suture.—Reniform.		
Symmetry viewed from pistil end.—Symmetric or slightly asymmetric.		
Shape of pistil end.—Slightly depressed.	65	
Depth of stem cavity.—Medium, about 1.8 mm.		

What is claimed is:

1. A new and distinct variety of cherry tree as herein described and illustrated.
